DOOR-OPERATING MECHANISM FOR TILTING FURNACES.

1,376,819.

Specification of Letters Patent.

Patented May 3, 1921.

Application filed May 10, 1919. Serial No. 296,165.

To all whom it may concern:

Be it known that I, JAY S. MCCLIMON, a citizen of the United States, residing at Cleveland, in the county of Cuyahoga and 5 State of Ohio, have invented a certain new and useful Improvement in Door-Operating Mechanism for Tilting Furnaces, of which the following is a full, clear, and exact description.

10 This invention relates to a door operating mechanism for tilting furnaces such as open hearth or other furnaces of the rolling or tilting type, and having one or more mechanically operated doors.

15 The principal object of the invention is to provide a door elevating or operating mechanism which will not be affected by the tilting of the furnace, so that it will be possible to readily shift the door or doors 20 in any position of the furnace.

Other objects are to provide door operating mechanism, light in weight, small in compass, and simple in construction.

Still further the invention aims to provide 25 a door operating mechanism, the main operating parts of which may be positioned at a point such that they will not be adversely affected by the heat of the furnace, and also to provide door shifting mechanism 30 so arranged and operated that it makes possible the installation of a satisfactory counterweight device which will not be affected by the tilting of the furnace.

The invention may be briefly summarized 35 as consisting in certain novel details of construction and combinations and arrangements of parts which will be described in the specification and set forth in the appended claims.

40 In the accompanying sheets of drawings wherein I have shown the preferred embodiment of my invention, Figure 1 is a sectional view through a furnace equipped with three charging doors and with my improved door operating mechanism; Fig. 2 is a view looking toward the front of the furnace, omitting the power operated mechanism which actuates the lines or cables connected to the doors; and Fig. 3 is a top plan view showing merely the front edge of the furnace structure.

In the drawings, 10 represents a furnace of the type with which my invention has utility, the furnace here shown being, by 55 way of example, an open hearth furnace.

It is in this instance provided with a pouring spout 11 on the rear side, and with a series of charging doors 12, in this case, three in number, (see particularly Fig. 2) on the front side. The number of charging 60 doors may, however, be greater or less than the number shown.

The furnace is mounted for tilting movement on two or more stands 13, suitably spaced apart, having flat upper surfaces on 65 which arc-shaped or rounded rockers 14, secured to the base of the furnace, are adapted to roll when the furnace is tilted by mechanism shown conventionally and indicated by the reference character 15. 70

The doors 12 slide in frames 16 which are substantially vertical when the furnace is in normal position. The doors are adapted to be raised and lowered individually by means of three lines or cables 17, which are attached at 18 to the upper portions of the doors as shown in Fig. 2, and then extend upwardly in parallel relation to, and around sheaves 19, mounted at the front and on top of the furnace 10. From these sheaves the 80 cables extend laterally around sheaves 20, mounted in a housing 21, at the top and laterally of the doors 12, and from these sheaves 20 the lines or cables extend downwardly to, and around sheaves 22 coaxially 85 supported at the lower front part of the furnace.

If the lines extended from the sheaves 22 direct to the line or cable operating devices, it is obvious that the doors could not be 90 satisfactorily operated when the furnace is tilted, since the sheaves 22 are located a considerable distance from the center line of the rolling base portions 14 of the furnace, and hence have considerable lateral movement forwardly or rearwardly when the furnace is tilted. 95

To overcome this objection, and to provide means whereby the tilting of the furnace will have practically no effect on the lines 100 connected to the doors, and so that the latter may be operated as readily when the furnace is tilted as when in normal position, I provide beneath the furnace on the center line of the rolling base portions or rockers 105 14, sheaves 23, and extend the cables from the sheaves 22 rearwardly or inwardly around the sheaves 23, and then forwardly to the front of the furnace. The axis of these sheaves 23 is located at what may be 110

termed the neutral point or axis of the furnace, which is the line having the least lateral movement of any point of the furnace for a given amount of rotation. That is to say, when the furnace is being tilted its maximum amount from normal position, or is tilted back to normal position, the axis of these sheaves 23 is moved laterally, *i. e.* forwardly or rearwardly a very slight distance only, and this has no adverse effect at all on the door shifting mechanism.

From the sheaves 23, the lines pass to the operating mechanism proper, which may be of any type or form, and may be located at any distance from the furnaces, so that this mechanism will not be affected by the heat of the furnace. In this instance, the lines extend from the sheaves 23 forward in substantially a horizontal direction and pass about sheaves 24, located a suitable distance in front of the furnace, then upwardly around sheaves 25, and then to the mechanism which pulls in the lines to elevate the doors, or pays them out to allow the doors to be lowered. The particular mechanism shown for this purpose forms no part of the present invention but is claimed in a separate application filed of even date herewith. Briefly stated, this mechanism includes (see particularly Fig. 3) a horizontal shaft 26, driven by a motor 27, and provided along its length with oppositely facing bevel friction disks 28, one pair provided for each furnace door. These pairs of disks 28 are sleeved together, and each pair is splined to the shaft. The three pairs may be shifted lengthwise of the shaft by levers 29, shown most clearly in Fig. 1. Coöperating bevel friction disks 30 are arranged one opposite each pair of disks 28, and each is designed to be driven in one direction by one disk 28, and in the opposite direction by the other disk 28. These bevel friction disks 30 are designed to rotate short shafts which extend at right angles to the shaft 26, and are connected by worm or other form of gearing to shafts provided with cranks 31, each crank being located opposite one of the last mentioned sheaves 25, and each having connected to it the end of one of the door operating lines 17, in the manner clearly shown in Figs. 1 and 3. These cranks in the normal operation of the machine, swing through an arc of one hundred and eighty degrees, swinging in one direction to raise the doors, and in the reverse direction to close them. It will be understood that the doors may by this mechanism be individually raised or lowered with the same motor driven shaft which may be driven continuously in the same direction, and need not be reversed.

While the mechanism here shown and above described for operating the lines 17 is preferred, as far as the present invention

is concerned, any other suitable mechanism which answers the requirements may be used instead.

It will be observed that the sheaves 25 in front of the cranks, and the lower sheaves 24 are spaced apart a farther distance than the sheaves 22 and 23 at the lower part of the furnace, and to permit the lines to diverge as shown in Fig. 3, the two outermost lines engage horizontal sheaves 32, shown in Fig. 3.

With the arrangement of lines and sheaves shown, I am enabled to very effectively counterbalance the doors, and this is done by means of counterweights 33, one of which will be provided for each line, these counterweights being supported on counterweight lines 34, each of which is attached at 35 (see Fig. 1) to one of the lines 17 along the substantially horizontal portion thereof extending between the sheaves 23 and 24. The counterweight lines 34 pass over sheaves 36 which together with the sheaves 24 are rotatably mounted in suitably spaced relationship in a frame 37, shown in Figs. 1 and 3.

With the mechanism above described, and especially by reason of the arrangement of the lines 17 and sheaves, and particularly by reason of the sheaves 23, located beneath the furnace at or substantially at the center line of the rocking base portions, any of the doors may be operated, *i. e.* raised or lowered as readily when the furnace is tilted as when in normal position. For this reason my improved door shifting mechanism has distinct advantage over all of those of which I am aware, and which have been tried out heretofore, and it has also the further advantage that it is economical in weight, small in compass, requires no excessively heavy supporting parts on the furnace as have many of the prior devices, and is not adversely affected by the heat of the furnace.

Having described my invention, I claim:

1. The combination with a tilting furnace having a door adapted to be raised and lowered, and having a base adapted to roll on a support, of a door shifting mechanism including a line connected to the door and extended beneath the furnace about a member located at or substantially at the center line of said furnace base, substantially as and for the purpose described.

2. The combination with a tilting furnace having one or more doors to be shifted, of a door shifting mechanism including a line attached to the door, and a sheave about which the line extends, said sheave being carried by and located beneath the furnace.

3. In combination with a furnace of the tilting type having one or more doors, door operating mechanism, a line extending from the door to the operating mechanism, and supporting sheaves for the line, one of the

sheaves being carried by and located beneath the furnace at a point such that it has relatively small lateral movement forwardly or rearwardly when the furnace is tilted.

5 4. The combination with a tilting furnace having a door to be shifted, of a door shifting mechanism including a line connected to the door, and a guide for the line located at the lower part of the furnace.

10 5. The combination with a tilting furnace having a door to be shifted, a door shifting mechanism and a line extending therefrom to the door, and a guide sheave for the line located at the lower part of the furnace beneath substantially the center thereof.

15 6. In combination with a tilting furnace having a door to be shifted, of a door shifting mechanism including a line attached to the door, and a guide sheave about which the line passes, said sheave being movable with the furnace and located at substantially the point of minimum lateral movement when the furnace is being tilted.

20 7. In combination with a furnace of the tilting type having a base adapted to roll over a support, and having one or more doors to be elevated, mechanism for operating the door or doors, and a line extending from the said mechanism forwardly beneath

the furnace around a sheave carried thereby, then laterally and upwardly to a furnace door.

25 8. In combination with a furnace of the tilting type, having one or more doors to be raised and lowered, door operating mechanism, a line for operating a door, a plurality of sheaves for the line, said line extending from said mechanism to the furnace, around said sheaves and then to the door, one of said sheaves being carried by the furnace and located below substantially the center line thereof.

30 9. In combination with a furnace of the tilting type, having one or more doors to be raised and lowered, door operating mechanism, a line for operating a door, a plurality of sheaves for the line, said line extending from said mechanism beneath the furnace to one of said sheaves which is carried by and located below substantially the center line of the furnace, then extending from said sheave around other sheaves to the door, and a counterweight connected to the line between said sheave beneath the furnace and said mechanism.

35 45 50 55 In testimony whereof, I hereunto affix my signature.

JAY S. McCLIMON.
